UNITED STATES PATENT OFFICE

GROVER C. MILLER, OF SOUTH PASADENA, CALIFORNIA

AGAR COMPOUND

No Drawing.

Application filed September 29, 1926. Serial No. 138,576.

This invention relates to agar-agar compounds and is more particularly related to a compound of agar-agar formed into an emulsion as a thin liquid, preferably of approximately the density of water and is particularly adapted for use as a medical laxative compound for assisting the intestinal organs in performing their functions in a normal manner.

10 This application is for a medical compound of the nature disclosed in an application filed by me on or about Nov. 15, 1923, Serial No. 674,966.

15 Medical compounds formed in accordance with this invention are in the nature of a laxative as distinguished from a cathartic and which compound performs its function in a mechanical manner rather than by chemical stimulation of the colon or large intestine.

20 In the preparation of agar-agar liquid petrolatum compounds with water, there is a tendency to form a dense mass which is not mobile if there is added to the solution or mixture a quantity of agar-agar sufficient to perform the proper evacuating function of the large intestine.

25 When agar-agar is boiled with water and allowed to cool, either with or without agitation, there is formed a bulk which is of a jelly-like consistency or a coagulated mass which will not flow and which might be cut into pieces and handled in that matter.

30 In order to prepare an emulsion of agar-agar, mineral oil and water, there has heretofore been employed emulsifying agents, such as gums and the like, which were for the purpose of maintaining the mineral oil expanded within the agar-agar and water mixture or solution. These gums, however, are particularly susceptible to fermentation so that the entire product formed soon spoils when a gum is employed. It is not possible to prepare an agar-agar liquid petrolatum emulsion containing a relatively large quantity of agar-agar with this method so that the compounds prepared in accordance with this method fail to contain the requisite amount of agar-agar which is required in an effective agar-agar mineral oil emulsion.

35 I have found that in preparing an agar-

agar mineral oil composition, that if an acid is added to the composition during the heating of the agar-agar in the water, that there may be formed a mineral oil emulsion which is relatively stable and relatively mobile so that the same may be easily poured from a bottle or the like. The use of this acid, I have found, retards the tendency to form in the composition a fungus which results from apparent putrefaction of the compound when such as acid is not employed.

40 It is therefore an object of this invention to provide an agar-agar liquid petrolatum emulsion that is stable, which is relatively mobile, and in which the tendency to form fungus is eliminated by adding to the composition during the preparation an acid which, due to the hydrogen ion content, reduces the density of the composition from a jelly-like substance to a relatively mobile liquid, which aids in the maintaining of a stable emulsion, and which prevents the formation in the compound or on the compound of fungus, due to apparent putrefaction thereof.

45 Another object of this invention is to provide a medical compound which is of palatable form, and in which compound preservatives are added for preserving the compound over a long period of time.

50 Another object of this invention may be to provide agar-agar liquid petrolatum compound in which there is provided lactic acid for reducing the density of the compound, preventing the formation of fungus and for rendering the emulsion formed stable and for the further purpose of aiding digestion of a person taking the compound.

55 Other objects and advantages of this invention, it is believed will be apparent from the following detailed description of a preferred embodiment thereof.

60 In accordance with this invention, agar-agar is added to boiling water and the mixture is boiled until the agar-agar is dissolved, which, it has been found, requires approximately fifteen minutes when an acid is added to the composition during the boiling thereof. During the dissolving of agar-agar in the water, salt (sodium chloride) is added to the solution and serves as a flavoring and

also to some extent as a preservative. During the dissolving of the agar-agar in the water, sodium benzoate is also added, and this sodium benzoate serves as an additional preservative. After the solution has been 5 boiled for about fifteen minutes, sugar and vanillin are added and the entire bulk is transferred to a mixing or agitating machine in which the same is thoroughly agitated. During the agitation of the solution, 10 liquid petrolatum or white mineral oil is added to the solution and the agitation is continued for approximately thirty minutes. Glycerine and additional flavorings or strong 15 flavorings are then added to the solution and the agitation thereof is continued until the entire mixture is cool.

The acid employed in this composition may be any acid fit for internal use and only a 20 relatively small quantity is employed. The flavoring and preservatives added to this composition, may be added during any step of the process of forming the same and are merely for the purpose of rendering the compound 25 more palatable and for preserving the same.

I have found that in such a preparation, lactic acid serves to the best advantage in the forming of the proper emulsion, as this acid 30 not only functions equally well with other acids to reduce the viscosity of the emulsion or to render the same relatively mobile, but prevents the formation of fungus and aids in the maintaining of a stable emulsion and the 35 lactic acid when taken into the system aids the digestion so as to increase the effectiveness of the compound when employed as a laxative when cleaning out the entire system.

In the foregoing, lactic acid is set forth 40 merely for illustrative purposes and any other acid fit for internal use may be employed in the preparation of this compound for the purpose of producing a stable relatively mobile agar-agar liquid petrolatum emulsion. 45 The following is given as an illustrative example of the ingredients and the proportions thereof that I have found to produce a most efficient agar-agar liquid petrolatum emulsion. The following quantities are for the 50 preparation of one pint of emulsion:

Sodium chloride	12	grains
Sodium benzoate	20	grains
Agar-agar	120	grains
Mineral oil	8 1/2	ounces
Lactic acid	5	drops
Glycerine C. P.	1/2	ounce
Sugar	1/4	ounce
Vanillin	1/2	grain
Fontan and muscat	1	drop
and water sufficient to make a pint.		

The fontan and muscat set forth in the above example are synthetic apricot and muscat grape flavorings, and equal proportions 65 of each of these synthetic flavorings being

mixed together and one drop of the resultant mixture employed. Glycerine is employed in the above composition in order to reduce the sugar required in order to make a palatable composition and the use of glycerine also 70 renders the emulsion produced more smooth. Glycerine also serves as a preservative and in taking the place of a quantity of sugar not only serves the place as a preservative and flavoring but also reduces the amount of sugar 75 required thereby, reducing the tendency of the compound to ferment. The agar-agar mineral oil composition produced is a more effective laxative compound than either mineral oil or agar-agar taken separately and 80 also possesses particular advantages over each of these substances used independently. Agar-agar taken independently is a rasping unpleasant substance which absorbs water from the intestinal tracts in large quantities. 85 Mineral oil taken separately has a disagreeable tendency to "leak". The composition formed in accordance with this invention eliminates the tendency of agar-agar to absorb, in such large quantities, water from the 90 intestinal tracts, is a smooth and even composition which does not rasp and as the agar-agar is introduced into the intestinal tracts, the same expands to the absorption of water 95 so that the tendency of mineral oil to "leak" is overcome.

The composition embodying this invention is most advantageously taken in the morning prior to eating breakfast and in order to produce the best results should be followed by a 100 glass of water. The agar-agar and mineral oil, the principal components of the composition embodying this invention, are substances which are unaffected by the digestive system so that the same pass freely through the 105 stomach.

Having fully described a preferred embodiment of my invention, it is to be understood that I do not wish to be limited to the exact details herein set forth as the same may 110 possibly be varied without departing from the spirit of my invention as set forth in the appended claims.

I claim:

1. An agar-agar liquid petrolatum emulsion, comprising agar-agar, water, liquid petrolatum, and an acid. 115
2. An agar-agar liquid petrolatum emulsion, comprising agar-agar, water, mineral oil, an acid, and a preservative. 120
3. An agar-agar liquid petrolatum water emulsion, comprising agar-agar, water, an acid, liquid petrolatum, a preservative, and flavoring. 125
4. An agar-agar liquid petrolatum water emulsion, comprising agar-agar boiled in water, lactic acid and liquid petrolatum mixed together to form an emulsion. 130
5. An agar-agar liquid petrolatum water emulsion, comprising agar-agar in an aque-

ous acid solution to which liquid petrolatum has been added to form an emulsion.

5 6. An agar-agar liquid petrolatum water emulsion, comprising an aqueous acid emulsion of liquid petrolatum and agar-agar to which preservative and flavoring materials have been added.

10 7. An agar-agar liquid petrolatum water emulsion, comprising an aqueous lactic acid emulsion of mineral oil and agar-agar to which sodium benzoate, glycerine and flavoring material have been added.

Signed at Los Angeles, California, this 24th day of September, 1926.
